CLAIM

The ornamental design for a camera housing, as shown and described.

DESCRIPTION

FIG. 1 is a front, top and right side perspective view of a camera housing showing our new design; FIG. 2 is a front, bottom and left side perspective view thereof;

FIG. 3 is a rear, bottom and right side perspective view thereof;

FIG. 4 is a rear, bottom and left side perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines depict portions of the camera housing in which the design is embodied that form no part of the claimed design.

1 Claim, 10 Drawing Sheets
